VALVE GRINDER

Fred W. Miller *Trustor*
By *Glenn S. Noble* *Atty.*

UNITED STATES PATENT OFFICE

FRED W. MILLER, OF CHICAGO, ILLINOIS

VALVE GRINDER

Application filed November 19, 1928. Serial No. 320,416.

Valves for internal combustion engines are usually provided with oppositely disposed holes or recesses or with central slots which are adapted to be engaged by suitable grinding tools for grinding the same. Such holes are spaced differently in different sized valves and may be spaced differently in the same sized valves of different manufacturers. Adjustable grinding tools have, therefore, been provided for grinding valves, but such tools have usually been comparatively expensive to manufacture and not satisfactory in use.

The objects of the present invention are to provide an improved tool for grinding valves or the like; to provide a valve grinding tool which will be very inexpensive to manufacture and which will be durable and efficient in use; to provide a valve grinding tool having a minimum number of parts and having novel adjusting means for adjusting the bits which engage with the holes; to provide a valve grinder having a screw driver bit and also having adjustable hole engaging bits; and to provide such other improvements in construction and desirable features as will appear more fully from the following description.

In the accompanying drawings illustrating this invention,

Figure 1 is a front view of the tool shown in position for grinding a valve with parts broken away for convenience in illustration;

Figure 2 is a sectional view taken on the line 2—2 of Figure 1;

Figure 3 is a sectional view taken on the line 3—3 of Figure 1;

Figure 4 is a detail of the central or screw driver bit; and

Figures 5 and 6 are details of the adjusting bits.

Although the tools may be made in any desired sizes, the drawings are on a somewhat enlarged scale of the size most commonly used.

As shown in these drawings, 7 is the shank or shaft of any suitable form of brace which for convenience is shown as being broken away. The shank is provided at its lower end with a slot 8 for receiving the central or screw driver bit 9 and the adjusting bits

10, the latter being duplicates. The central bit 9 has an upwardly extending portion 11 which is provided with a hole 12 for receiving a cotter pin or fastening member 13 which holds the bits in the shank. The central bit 9 also has a downwardly extending projection 14 for engagement with slots in the valves so that it may be used as a screw driver bit for valves having such slots. The bit 9 also has a series of evenly spaced holes 15 which are adapted to be engaged by similarly spaced projections 16 on the bits 10. The projections 16 are preferably formed integrally with the bits 10, being punched out from the metal of the bit plate and are arranged in alignment in order to register with the holes 15 in the central or screw driver bit 9, the bits 10 have projections 17 for engagement with the holes 18 in the valves 19, as shown in Figure 1. When the bits are assembled with the projections on the adjusting bits in engagement with the holes in the center bit, the bits are inserted in the slot 8 and the cotter pin 13 placed in position which holds the bits in the brace. The bits are preferably held somewhat loosely on the pin so that the end bits are free to adjust themselves to the valve as the grinding operation takes place. The grinding is, of course, performed in the usual manner which is familiar to those cognizant with such operations. When the tool is to be adjusted for differently spaced holes in the valve, the bits are removed and the adjustable ones moved inwardly or outwardly to the proper size, and the projections brought into engagement with different holes in the center bit, these holes and projections being arranged sufficiently close together to provide for the usual necessary adjustments.

If the screw driver bit is to be used, the side or adjustable bits are turned with their projections 17 extending upwardly so that they are out of the way and will not interfere with the engagement of the screw driver bit with the valve.

In some instances adjustment of the bits might be provided by merely having holes in one member and projections on the other member, and other changes or modifications may suggest themselves as coming within the

scope of this invention which I do not wish to limit to the exact construction herein shown and described, except as specified in the following claims, in which I claim:

- 5 1. A valve grinder comprising a brace having a slot in the shank thereof, a central bit having a series of longitudinally arranged holes therein, means for securing said bit in the slot, and side bits having series of longitudinal projections adapted to engage with said holes, said side bits being held in engagement with the center bit by the sides of the slot.
- 10 2. A valve grinder comprising a brace having a slot in the end thereof, a screw driver bit engaging with said slot and projecting beyond the end of the brace, a pin for holding said bit in position in the brace, said bit having a plurality of holes arranged in alignment at right angles to the brace, side bits each having a plurality of longitudinally arranged projections engaging with the holes in the screw driver bit for holding them in adjusted position and also having projections 25 for engagement with holes in the valve to be ground, said side bits fitting closely between the screw driver bit and the sides of the slot.
- 30 3. A device as per claim 2 in which the projections on the bits for engagement with the holes are formed by being punched out of a plate forming the bit.
- 35 4. A tool for grinding valves comprising a brace having a shouldered slot in the end thereof, a central screw driver bit having a plurality of longitudinally arranged holes, means for securing said bit in the slot, adjusting bits fitting in the slot and engaging with said shoulders and having projections 40 for engagement with holes in the valve, and projections on the adjusting bits which engage with the holes in the screw driver bit for holding the adjusting bits in adjusted position with respect to the screw driver bit, said 45 adjusting bits being adapted to be turned to bring their projections out of engaging position.
